CLAIM

The ornamental design for an electrical connector, as shown and described.

DESCRIPTION

FIG. 1 is a top, left, front perspective view of an electrical connector according to one embodiment of our design;

FIG. 2 is another top, left, front perspective view thereof;

FIG. 3 is a bottom, right, rear perspective view of thereof;

FIG. 4 is another bottom, right, rear perspective view of thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof;

FIG. 10 is a bottom plan view thereof;

FIG. 11 is a top, left, front perspective view of an electrical connector according to another embodiment of our design;

FIG. 12 is another top, left, front perspective view thereof;

FIG. 13 is a bottom, right, rear perspective view of thereof;

FIG. 14 is another bottom, right, rear perspective view of thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof; and,

FIG. 20 is a bottom plan view thereof.

The broken line portion in the drawings illustrate portions of the electrical connector that form no part of the claimed design.
